UNITED STATES PATENT OFFICE

90,511

DESIGN FOR A DISPLAY STAND

Harry E. Shaw, Grand Rapids, Mich.

Application June 14, 1933. Serial No. 48,394

Term of patent 7 years

To all whom it may concern:

Be it known that I, HARRY E. SHAW, a citizen of the United States, residing at the city of Grand Rapids, in the county of Kent and State of Michigan, have invented a new, original, and ornamental Design for a Display Stand, of which the following is a specification, reference being had to the accompanying drawing, forming a part thereof.

The figure is a perspective view of a display stand, showing my new design.

I claim:

The ornamental design for a display stand, as shown.

HARRY E. SHAW.
